UNITED STATES PATENT OFFICE.

FRANK KLEINSCHMIDT, OF DOYLE, NEW YORK.

EVAPORATOR.

No. 856,262.

Specification of Letters Patent.

Patented June 11, 1907.

Application filed February 27, 1906. Serial No. 303,295.

To all whom it may concern:

Be it known that I, FRANK KLEINSCHMIDT, a citizen of the United States, residing at Doyle, in the county of Erie and State of New York, have invented certain new and useful Improvements in Evaporators, of which the following is a specification.

My invention relates to improvements in evaporators, for evaporating glue, and other substances.

The objects of my invention are, the production of an evaporator of simple construction in which a revolving agitator is provided with heads connected by steam-conducting or heating pipes and to provide the inlet head with a steam distributer so that the steam is distributed to the various heating-pipes in approximately equal quantities, thereby avoiding the uneven heating of said pipes which would cause them to warp and break at the joints; and to otherwise improve on evaporators now in use.

With these objects in view the invention consists in the combination, construction, and arrangement of parts to be hereinafter described and more particularly pointed out in the appended claims.

In the drawings,—Figure 1 is a central longitudinal section through an evaporating apparatus embodying my invention. Fig. 2 is a vertical transverse section taken on line $z-z$, Fig. 1.

Referring to the drawings in detail, corresponding numerals of reference refer to corresponding parts in both figures.

The reference numeral 1 designates the chamber which is closed and provided at its lower end with hopper extensions 2, having secured thereto outlet-pipes 3 for the removal of the evaporated substance from the chamber. Said pipes may be provided with suitable valves to confine the substance within the chamber; but as these are common and form no part of my invention, they are omitted from the drawings. The chamber, as shown in preferred form, is constructed of three sections 4. However, two or more than three sections may be used if desired; each section having a hopper-bottom. The sections are provided with flanges 5 by means of which they are bolted together. The chamber is of considerable height in comparison to the width, and the upper and lower walls are preferably rounded. The end walls of the chamber are bolted to the outer

flanges of the end sections; all seams in the chamber being water and steam-tight. The length of the chamber may be of any size and depends on the number of sections employed. 60 One end wall is provided with a charging-pipe 6, controlled by a valve (not shown).

The upper wall of the chamber is provided with two or more vapor escape pipes 7 through which the water element eliminated from the 65 substance within the chamber is permitted to pass. As shown in preferred form in the drawings, each section of the chamber is provided with an escape outlet, and all pipes connected to said outlets merge into a single 70 vapor escape pipe 7^a through which the vapors escape into a vacuum chamber, as is common.

Arranged lengthwise in the lower end of the chamber is a combined heating and agitating-apparatus 8 comprising an inlet-head 9, an outlet head 10, and steam-pipes 11 connecting said heads. The inlet-head is provided with a center inlet tube 12, which passes through a stuffing-box 13 in the adjacent end wall of the chamber, and the outlet-head is provided with a center outlet-tube 14 passing through a stuffing-box 15 in the other end wall of the chamber. Said tubes serve as a shaft for the heating and 80 agitating-apparatus, to which power may be transmitted in any practicable manner to revolve the same. The relative arrangement of the heating-pipes which connect the heads is such, that on revolving the heating-apparatus, the substance is thoroughly agitated 85 to aid in the elimination of the water-element.

As the heating-pipes are connected to the heads at different points, I make provision 95 for distributing the steam entering the inlet-head through tube 12, to prevent the passing of more steam through the pipes nearer said tube than through the pipes more remote therefrom. For this purpose I provide a distributor 16 within the head in the form of a chamber having its peripheral wall provided with perforations 17 through which the steam issues; the steam being thereby distributed and expands within the head so 100 as to pass in approximately equal proportions through the heating-pipes. In this manner the various pipes are subjected to like temperature and necessarily compelled to expand equally; thereby preventing warping 105 of any of the pipes, which would cause the heads to be subjected to uneven and twisting

strain, causing the pipe 6 to become loosened from the heads and consequently permitting the escape of steam into the chamber, in consequence of which water-elements would be 5 added to the substance in greater quantities than could be eliminated.

The outlet-tube 14 is journaled to revolve in a fixed support 18, and secured to said tube and bearing against opposite sides of 10 said support, are collars 19, which prevent lengthwise movement of the outlet-tube. In consequence of this arrangement, the heating-apparatus must expand in the opposite direction.

15 Entering the outlet-tube through a stuffing-box 20 therein is a steam outlet-pipe 21 which is provided at its inner end with a depending leg 22 extending into the outlet head to within a short distance of the bottom. 20 of the latter, said leg terminating by preference in a flaring mouth. The steam entering the outlet-head through the heating-pipes secured thereto passes out through pipe 21, and by reason of said pipe extending closely to 25 the peripheral wall of the head, the water of condensation remaining in said head can readily escape. By reason of the pipe 21 passing through a stuffing-box on the outlet center-tube, the latter may turn with the heating-apparatus while said pipe remains stationary.

30 The substance within the chamber has its level a distance from the top of the agitator, and when subjected to heat and agitated, it has a tendency to boil and enter the escape 35 pipes 7. To prevent this, I suspend a baffle-plate 23 centrally from the top wall by means of bolts 23^a, so as to hang in a direct line with the escape-pipes. On either side of said plate and slightly beneath, side baffle-plates 40 are arranged and riveted to the sides of the chamber. Said side plates are inclined toward the longitudinal center of the chamber and overlap the center baffle-plate; the overlapping portions being separated from 45 the center-plate by intervening spaces 25. In this manner a circuitous passage is provided for the vapors and the substance within the chamber, when boiling strikes against the baffle-plates and is checked in its upward course. The substance, when striking the center baffle-plate, drips onto the inclined side plates and is directed back into 50 the chamber.

By the employment of a closed chamber

having the vapor-escape pipes and the charging pipe, the apparatus may be run continuously, the chamber being charged as the substance is drawn off through the outlet-pipes 3. 55

Having thus described my invention, what I claim is,—

1. In an evaporator, the combination of a chamber, and a heating-apparatus within the chamber comprising a hollow inlet-head, a hollow outlet-head, and a series of heating-pipes connecting said heads, said inlet-head 65 having a steam-inlet and a steam-distributer into which said inlet opens and which serves to distribute the steam to said heating-pipes, and said outlet head having a steam-outlet.

2. In an evaporator, the combination of a 70 chamber, and a heating-apparatus within the chamber comprising a hollow inlet-head, a hollow outlet-head, and a series of heating-pipes connecting said heads, said inlet-head having a steam-inlet and a perforated chamber 75 into which said inlet opens and which serves to distribute the steam to said heating-pipes, and said outlet head having a steam-outlet.

3. In an evaporator, the combination of a 80 chamber, and a heating apparatus within the chamber comprising a hollow inlet-head, a hollow outlet-head, and a series of heating-pipes connecting said heads, said inlet-head having a steam -inlet and also a chamber 85 therein into which said inlet opens and which has peripheral apertures for the escape of steam into said head, and said outlet head having a steam-outlet.

4. In an evaporator, the combination of a 90 chamber, and a heating apparatus within said chamber comprising hollow cylindrical heads connected by parallel pipes, one of said heads having an inlet-tube and a steam-distributer in the form of a chamber extending into said 95 hollow head from one wall of the latter, said chamber having its peripheral wall provided with perforations and the said inlet - tube opening thereinto, and the other head having a steam-outlet.

100 In testimony whereof, I have affixed my signature in the presence of two subscribing witnesses.

FRANK KLEINSCHMIDT.
